(57) **CLAIM**

The ornamental design for a cart body for a medical waste disposal system, as shown and described.

DESCRIPTION

FIG. 1 is a perspective view of a cart body for a medical waster disposal system showing my new design;
 FIG. 2 is a perspective view of the cart body;
 FIG. 3 is a side elevation view of FIG. 2;
 FIG. 4 is a rear elevation view of FIG. 2;
 FIG. 5 is a front elevation view of FIG. 2;
 FIG. 6 is a top plan view of FIG. 2; and,
 FIG. 7 is a bottom plan view of FIG. 2.

The features indicated in the figures in broken lines form no part of the claimed design.
